CONVERSION OF HYDROCARBONS

Harold V. Atwell, White Plains, N. Y., assignor
to Process Management Co. Inc., New York,
N. Y., a corporation of Delaware

Application July 29, 1937, Serial No. 156,272

4 Claims. (Cl. 196—10)

My invention relates in general to the conversion of normally gaseous hydrocarbons and more particularly to a unitary process for the production of normally liquid hydrocarbons suitable for use as motor fuel from lighter gaseous hydrocarbons such as ethylene.

It has been shown that normally gaseous hydrocarbons can be polymerized under suitable conditions to yield normally liquid products. In general, however, such known processes of either catalytic or non-catalytic types have stressed the processing of higher molecular weight normally gaseous hydrocarbons. The catalytic polymerization processes, for example, have been shown to be best suited to the polymerization of unsaturated hydrocarbons having three, four or more carbon atoms to the molecule, and the presence of ethylene in the hydrocarbons being processed greatly reduces the efficiency of such a process. Non-catalytic processes, although less restricted to the processing of particular types of normally gaseous hydrocarbons, are more particularly directed to the processing of the higher molecular weight hydrocarbons.

A principal object of my invention is to provide a unitary process wherein normally gaseous hydrocarbons predominating in ethylene are converted to normally liquid products suitable for use as motor fuel.

A further object of my invention is to provide a unitary process for the conversion of normally gaseous hydrocarbons comprising substantial amounts of ethylene to normally liquid products wherein the ethylene is initially converted, in the presence of a suitable promoter, to unsaturated hydrocarbons of higher molecular weight and wherein normally gaseous hydrocarbons comprising unsaturated hydrocarbons of higher molecular weight so produced are subjected to polymerizing conditions of temperature and pressure to effect the conversion of normally gaseous hydrocarbons to normally liquid products suitable as motor fuel.

Another object of my invention is to provide a unitary process for the polymerization of normally gaseous hydrocarbons wherein normally gaseous hydrocarbons comprising both saturated and unsaturated hydrocarbons are converted to normally liquid products and wherein ethylene, heretofore found difficult to convert because of its apparent refractoriness, is converted in continuous stream to unsaturated hydrocarbons of higher molecular weight suitable for treatment in the polymerization phase of the cycle thus obtaining greater yields of liquid products than

have heretofore been obtained from a similar raw material.

Another object of my invention is to provide a unitary process for the conversion of normally gaseous hydrocarbons predominating in lower molecular weight unsaturated hydrocarbons to normally liquid products wherein the normally gaseous hydrocarbons are treated to effect conversion of the lower molecular weight unsaturated hydrocarbon to unsaturated hydrocarbons of higher molecular weight with the simultaneous production of olefin oxides, for example ethylene oxide, capable of promoting polymerization reactions and wherein normally gaseous hydrocarbons comprising the higher molecular weight unsaturates and the olefin oxides produced therewith are subjected to conditions of temperature and pressure whereby conversion of normally gaseous hydrocarbons to normally liquid, stable, gasoline-like products of high anti-knock value is effected.

My invention contemplates a process for the conversion in a continuous stream of normally gaseous hydrocarbons comprising substantial amounts of ethylene, or consisting essentially or principally of ethylene to normally liquid products in the gasoline boiling range, wherein the normally gaseous hydrocarbons are treated, in the presence of a suitable promoter to convert ethylene to unsaturated hydrocarbons of higher molecular weight. The normally gaseous hydrocarbon stream comprising the higher boiling unsaturates so produced is subjected to conditions of temperature and pressure whereby normally gaseous hydrocarbons are converted to normally liquid products in the gasoline boiling range. The conversion products are fractionated to separate normally liquid products from the normally gaseous products. The normally gaseous reaction products are again fractionated to segregate a fraction predominating in hydrocarbons having three or more carbon atoms to the molecule which may be recycled to the thermal conversion zone. The remaining normally gaseous products comprising ethane, ethylene, hydrogen and methane are further fractionated to segregate a fraction predominating in ethane and ethylene which is recycled to the primary conversion zone wherein ethylene is converted to unsaturated hydrocarbons of higher molecular weight. If desired the hydrocarbon fraction predominating in ethane and ethylene may be treated to effect a concentration of the ethylene before recycling the fraction to the primary conversion zone.

The normally gaseous hydrocarbons charged to my unitary process may be those obtained from any available source; for example, the normally gaseous products from refinery processes such as the distillation or cracking of hydrocarbon fluids, the stabilization of natural gasoline, etc. The invention is especially directed to the treatment of gases in which the concentration of ethylene is particularly high. My invention, therefore, has the further advantage of being able to operate on the effluent gases normally eliminated from some polymerization units because of their high ethylene content.

When charging those normally gaseous hydrocarbons for which my process is especially adapted, that is, those containing substantial amounts of ethylene, the hydrocarbons in admixture with controlled quantities of a promoting agent capable of converting ethylene to unsaturated hydrocarbons of higher molecular weight are passed through a preheating coil and discharged into a reaction zone, under conditions which will effect the conversion of ethylene to unsaturated hydrocarbons of higher molecular weight.

Suitable agents for promoting the conversion of ethylene to unsaturated hydrocarbons of higher molecular weight are: oxygen or an oxygen-containing gas, halogens, sulfur or compounds of these elements such as SO_2 or S_2Cl_2 . Of these oxygen is preferred. When oxygen is used as the activating agent there will be produced simultaneously with the conversion of ethylene to unsaturated hydrocarbons of higher molecular weight small quantities of olefine oxides, such as ethylene oxide, which are of especial value in promoting the subsequent conversion of normally gaseous hydrocarbons to normally liquid products.

The invention will be more fully understood from the following description read in connection with the accompanying drawing showing diagrammatically an elevation of one form of apparatus for carrying out the process of the invention.

Referring to the drawing, normally gaseous hydrocarbons predominating in ethylene are drawn through line 1 from an outside source, not shown, and forced by means of pump 2 through line 4, controlled by valve 3, into a preheating coil 5 positioned in furnace 6. Prior to their entry into preheating coil 5, the hydrocarbon gases are mixed with an activating agent, for example oxygen, supplied from an outside source, not shown, through line 7 controlled by valve 8. The quantity of oxygen added to the charge may vary between 0.5% and 3%, and should preferably be about 1%, by volume of the charge passed into coil 5. The stream of hydrocarbons with the admixed oxygen is preheated in coil 5 to a temperature of approximately 750 to 1200° F., and at a low pressure ranging from slightly above atmospheric to about 100 pounds per square inch. The preheated gaseous mixture leaving coil 5 is passed through line 9 into the reaction chamber 10 wherein the conditions of temperature and pressure prevailing in coil 5 are maintained. Although in the specific example illustrating the invention the conversion of ethylene to unsaturated hydrocarbons of higher molecular weight is carried out in a reaction chamber, the invention is in no wise limited to the use of such reaction chamber, and the reaction may be effected in a separate coil or in a continuation of coil 5 itself. When the given temperature and pressure conditions are carefully maintained in coil

5 and reaction chamber 10, a substantial portion of ethylene, in the presence of the admixed oxygen, is converted in reaction chamber 10 to unsaturated hydrocarbons having three and four carbon atoms to the molecule. The gases are maintained in the reaction chamber 10 for a period of time sufficiently long to effect the desired conversion, which will normally not exceed about ten seconds. The mechanism of the reaction or reactions by which ethylene is converted in reaction chamber 10 to unsaturated hydrocarbons of higher molecular weight is not fully understood. It is probable that the presence of the oxygen promotes the disruption of the carbon to hydrogen linkages of the ethylene in a manner forming unstable radicals capable of recombining to form the higher molecular weight unsaturated hydrocarbons. It may well be that the oxygen enters into the formation of intermediate oxygenated compounds with ethylene which intermediate compounds then react to form the higher molecular weight unsaturated hydrocarbons. The process, however, is not limited to any particular theory of the many complex reactions which may take place at the given conditions of the invention to effect this phase of the process.

Although oxygen is preferred for promoting the conversion of ethylene to unsaturated hydrocarbons of higher molecular weight other promoters such as halogens, sulphur or compounds of these elements such as SO_2 or S_2Cl_2 may be used. When, as in the present instance, oxygen is used as the activating agent for the primary conversion operation there are formed, simultaneously with the higher molecular weight unsaturated hydrocarbons, lesser quantities of oxygenated hydrocarbons comprising olefin oxides, for example, ethylene oxide, as well as small amounts of hydrogen and oxides of carbon.

Reaction products comprising the higher molecular weight unsaturated hydrocarbons propylene and butylene, and the hydrogen and oxygenated products produced simultaneously therewith, comprising olefin oxides such as ethylene-oxide, are withdrawn from reaction chamber 10 through line 11 controlled by valve 12 and conducted to a heat exchanger 13 wherein the products are cooled by indirect heat exchange with a suitable cooling medium which may be fresh charge to the system. Additional cooling by means of indirect exchange not shown in the drawing may be resorted to if desired. To enable compression of the gaseous stream to that pressure desired in the subsequent phase of the process the gases are cooled in heat exchanger 13 to a temperature at which such compression can more easily be effected, for example, 300° to 500° F. The cooled stream is conducted from exchanger 13 through line 14 to compressor 15 wherein the gases are brought to a pressure of from 400 to 3000 lbs. and preferably about 1000 to 1500 lbs. The compressed gases are passed from compressor 15 through lines 16 and 17 into conversion coil 18 positioned in furnace 19 wherein the hydrocarbon stream is raised to a temperature of 750° to 1250° F. and preferably from 900° to 1050° F. to effect the conversion of normally gaseous hydrocarbons to normally liquid products in the gasoline boiling range. Normally gaseous hydrocarbons, substantially paraffinic in character, or containing both paraffins and olefins, may be drawn from an outside source through line 20 controlled by valve 21 and forced by means of pump 22 into line 17 wherein they

are mixed with the products resulting from the ethylene conversion operation. As an alternative to their direct introduction into the system through line 20 the normally gaseous hydrocarbons may, by means of connections not shown in the drawing, be preheated by passage through exchanger 13 and the preheated gases introduced into line 17. If desired, these additional hydrocarbons may be preheated by direct admixture with the hot reaction products emanating from reaction chamber 10 and the resulting mixed stream passed to compressor 15. For example, these additional hydrocarbons may be admixed with the hot products from chamber 10 by introduction through line 50, provided with valve 51, which connects with line 11. The conversion of normally gaseous hydrocarbons to normally liquid products effected in conversion coil 18 may be, as described, of the thermal type involving both polymerization and alkylation reactions although catalyst may be used to effect the desired conversion. The presence, in the conversion coil 18, of olefin oxides, for example ethylene oxide, produced in reaction chamber 10 simultaneously with the conversion of ethylene to unsaturated hydrocarbons of higher molecular weight, materially aids in promoting the conversion of normally gaseous hydrocarbons to liquid products. If the production of these olefin oxides in reaction chamber 10 should be below the quantity required for the desired promotional effect in the subsequent thermal conversion phase of the process, or if they should be completely absent due to the use of an activating agent other than oxygen in reaction chamber 10, olefin oxides, such as ethylene oxide, may be supplied from an outside source through line 23 controlled by valve 24 and admixed with the gaseous charge flowing through line 17 to the conversion coil 18.

Reaction products pass from conversion coil 18 through line 25 and are cooled to below an active polymerization temperature by indirect heat exchange in exchanger 26. Additional cooling or quenching of reaction products in line 25 by means not shown in the drawing may be resorted to if desired. The cooled reaction products pass into a fractionator 27 wherein normally liquid products having a boiling point above that of the gasoline boiling range are separated and withdrawn from the bottom through line 28 controlled by valve 29. Uncondensed vapors and gases are passed from the primary fractionator 27 through line 30 to fractionator 31 wherein normally liquid products in the gasoline boiling range are condensed and withdrawn from the bottom of fractionator 31 through line 32 controlled by valve 33. Normally gaseous reaction products comprising hydrocarbons having less than five carbon atoms to the molecule and hydrogen are passed from fractionator 31 through line 34 to another fractionator 35 wherein a fraction predominating in three and four carbon atoms to the molecule is segregated. This fraction is drawn from fractionator 35 through line 36 controlled by valve 37 and recycled to the thermal conversion zone 18 by means of pump 38 which forces the fraction through line 39 into line 17. Normally gaseous reaction products not condensed in fractionator 35 and comprising ethane, ethylene, methane and hydrogen are passed from fractionator 35 through line 40 into fractionator 41. In fractionator 41 a fraction predominating in ethane and ethylene 75 is segregated from the lighter gases comprising

methane and hydrogen which leave fractionator 41 through line 42 controlled by valve 43 and are eliminated from the system. The hydrocarbon fraction predominating in ethane and ethylene in liquefied condition is drawn from fractionator 41 through line 44 and forced by means of pump 45 through line 46 into line 4 leading to the ethylene conversion phase of the process. The ethylene-ethane fraction drawn from fractionator 41 may be subjected to any desired treatment, not shown in the drawing, whereby the ethylene in the fraction is concentrated before being returned to the ethylene conversion stage of the cycle. Such ethylene concentration could be effected, for example, by absorption of the ethylene by a suitable absorbing medium such as acetone, acetaldehyde or liquid acetylene with subsequent recovery of the absorbed ethylene which is then returned to the ethylene conversion zone.

Normally gaseous hydrocarbons predominating in or consisting essentially of ethylene are charged to the system, as has been pointed out above, through line 1. If it is desired to process normally gaseous hydrocarbons comprising substantial proportions of hydrocarbons having more than two carbon atoms to the molecule, or less than two carbon atoms to the molecule in addition to ethylene the charge may be introduced into the system through line 47 controlled by valve 48 and forced by means of pump 49 through line 50 into fractionator 35 to be subjected to fractionation therein together with the normally gaseous reaction products resulting from the thermal conversion operation.

Although in the specific example set forth to illustrate the invention the unsaturated hydrocarbons produced by the conversion of ethylene in the primary conversion phase of the process are converted to normally liquid products in a thermal conversion type of operation, it is to be understood that the process is not limited to the use of this particular type of operation to effect this phase of the process. The normally gaseous unsaturated hydrocarbons resulting from the conversion of ethylene into unsaturated hydrocarbons of higher molecular weight may be converted to liquid products in a polymerization operation of the catalytic type wherein the normal gaseous hydrocarbons are subjected to a temperature of from 300° to 600° F., preferably about 400° to 500° F., and a pressure of 50 to 500 pounds, preferably 100 to 200 pounds in the presence of an active polymerization catalyst such as phosphoric acid. While phosphoric acid is preferred, other catalysts such as aluminum chloride, alumina on silica, sodium aluminum chloride, sulfuric acid or similar catalysts may be used.

The invention as set forth is particularly applicable to the conversion, in the primary phase of the process, of ethylene to unsaturated hydrocarbons of higher molecular weight. I wish to point out that my process is not limited to the conversion of this particular unsaturate in this phase of the process and that, should it be desired, propylene or a higher unsaturate may be charged to the primary conversion zone of the process in place of the ethylene, or together with ethylene, to be converted to higher olefins without detracting from the effective operation of the process according to the invention.

As pointed out above, the presence of the olefin oxides, for example ethylene oxide, formed simultaneously with the higher molecular weight

unsaturated hydrocarbons in reaction chamber 10 are of particular value in promoting polymerization reactions either of the thermal or catalytic type. Furthermore, their presence in the system lends to the normally liquid polymers drawn from fractionator 31 through line 32 a high degree of gum stability. Products of polymerization containing olefin oxides may be mixed with cracked gasoline of a high unsaturate content 10 and the mixture digested at a moderately high temperature, for example, 400° to 700° F., at a moderately high pressure, for example, 500 to 1000 pounds for a sufficient period of time to effect the desired polymerization of gum-forming constituents in the mixture. A small amount of olefin oxides, for example, ethylene oxide from an outside source may be added to the mixture of polymer and cracked gasoline to promote the 15 complete polymerization of any potential gum-forming compounds in the gasoline blend.

Obviously many modifications and variations of the invention, as hereinbefore set forth, may be made without departing from the spirit and scope thereof, and therefore only such limitations should be imposed as are indicated in the appended claims.

I claim:

1. The method of converting normally gaseous hydrocarbons to normally liquid products which 30 comprises subjecting an ethylene-rich gaseous hydrocarbon mixture in admixture with oxygen to elevated temperature in a primary conversion zone to effect conversion of ethylene to normally gaseous olefin hydrocarbons having more than 35 two carbon atoms per molecule and olefin oxides, admixing the hot reaction products from said primary conversion zone with a gaseous hydrocarbon mixture containing hydrocarbons having more than two carbon atoms per molecule to reduce 40 substantially the temperature of said reaction products, and subjecting the resulting mix-

ture to elevated temperature under a pressure substantially greater than that maintained in said primary conversion zone whereby olefin oxides present in said mixture promote conversion of normally gaseous hydrocarbon constituents to normally liquid products.

2. The method in accordance with claim 1 wherein the pressure maintained in said primary conversion zone is not greater than from atmospheric to 100 pounds per square inch, and the 10 pressure applied to the reaction products therefrom is substantially greater.

3. The method of treating a hydrocarbon gas mixture comprising ethylene and hydrocarbons having at least three carbon atoms per molecule 15 which comprises treating said mixture to separate therefrom an ethylene-rich fraction and a C₃ fraction predominating in hydrocarbons having at least three carbon atoms per molecule, subjecting said ethylene-rich fraction in admixture with oxygen to elevated temperature in a primary conversion zone under conditions suitable to effect conversion of ethylene to normally gaseous olefin hydrocarbons having more than two carbon atoms per molecule and olefin oxides, 25 admixing the reaction products from said primary conversion zone with said C₃ fraction, and subjecting the resulting mixture to elevated temperature whereby olefin oxides present therein promote conversion of normally gaseous hydrocarbon constituents to normally liquid products.

4. The method in accordance with claim 3 wherein the reaction in said primary conversion zone is effected under relatively low pressure, the hot reaction products therefrom are admixed 35 with said C₃ fraction to substantially reduce the temperature of said reaction products, and the resulting mixture is subjected to elevated temperature at relatively high pressure to effect production of normally liquid products.

HAROLD V. ATWELL.
